UNITED STATES PATENT OFFICE.

HARVEY JAMES MILES, OF BECKENHAM, ENGLAND.

INDICATOR.

1,297,888.

Specification of Letters Patent. Patented Mar. 18, 1919.

Application filed December 5, 1916. Serial No. 135,237.

To all whom it may concern:

Be it known that I, HARVEY JAMES MILES, a subject of His Majesty the King of England, and resident of Beckenham, in the 5 county of Kent, Kingdom of England, have invented certain new and useful Improvements in Indicators, of which the following is a specification.

This invention relates to improvements in 10 calendars, calendar clocks, and generally in automatic, periodic, and intermittent feeding mechanism for a ribbon or tape of flexible material.

In the improved feeding-mechanism constructed according to the present invention 15 the ribbon or tape is allowed by an improved intermediate roller and escapement mechanism, which is automatically tripped at required times by uniformly moving 20 clockwork apparatus or its equivalent, to periodically wind onto a drum which is directly and removably mounted upon a spring barrel, such winding being caused by the action of the spring contained within 25 in said barrel, and its movements rendered equal at all the periodic stages by the action of the intermediate mechanism. The apparatus may be designed for use with 30 calendar clocks or calendars or for exhibiting and repeating or changing advertisements, or church, legal, commercial or other notifications.

The invention greatly improves upon the 35 calendar clocks now in use by providing apparatus which is of extremely simple and inexpensive construction, has very few parts so that it is much less liable to get out of order, and requires very little adjustment. Thus, in carrying out the invention 40 in connection with a calendar clock the names of the days of a week, the names of the months in a year and numerals are printed, painted or otherwise formed on a tape or band of any suitable material, and 45 the apparatus is released or actuated by suitable mechanism or gearing operatively connected with the mechanism of a clock to advance and change the calendar once a day. In this arrangement the separate

dates might be inscribed one underneath the 50 other and longitudinally on the tape or band in the following manner, for instance:

Saturday, January 1st.

Sunday, January 2nd.

Monday, January 3rd.

55

and so on throughout a complete year.

Thus the apparatus may be applied to an existing clock driven by a spring or weight, by electricity or otherwise in such manner 60 that it is caused to operate by the existing mechanism of the clock through the intermediation of a suitable motion-transmitting mechanism or gearing interposed between the apparatus and said clock mechanism. 65

If desired, however, the apparatus may be used without a time-keeping clock so as to form a separate mechanical calendar. In this case the apparatus may be mounted in a suitable case and be periodically released 70 by spring or weight driven mechanism similar to that of a clock and adapted to be wound up periodically, or by electrically controlled driving mechanism.

When used with an existing or specially 75 constructed clock or for advertising or like purposes, the band or tape is especially adaptable to be renewed at the end of each year or when otherwise desired, according to the purpose for which the apparatus is 80 used.

By the insertion of a specially prepared tape or band at the commencement of each year the difficulties encountered by reason 85 of the irregular lengths of months, the occurrence of leap years, and the like are avoided.

A suitable manner of applying the invention to a clock will now be described with reference to the accompanying drawings, in which:—

Figure 1 is an elevation of the improved apparatus for carrying and advancing a tape or band bearing the dates to be exhibited;

Fig. 2 is a plan of Fig. 1;

Fig. 3 is a sectional elevation about the line 3—3 of Fig. 2, and

95

Fig. 4 is an elevation, partly in section, illustrating the apparatus applied to a clock.

The tape or band *a*, bearing the data to be exhibited, unwinds from a spindle *b*, fitted with a removable finger nut *c*, on to a drum *d* directly and removably fitted on a barrel or cylinder *e* which latter is rotated in one direction by an internal spring wound up by a fly nut *f*. Reverse rotation of the cylinder *e* and drum *d* is prevented by means of a spring pressed pawl *g* engaging a ratchet wheel *h* secured to said cylinder. The periodical movement of the tape or band, owing to the tension of the spring in the cylinder *e*, is allowed for by means of an escapement consisting of a spring pressed double pawl *i* engaging a star wheel *j* secured to an intermediate roller or drum *k*, said drum being provided with teeth *l* or other projections for engagement within perforations *m* formed in the edges of the tape or band. The tape or band passes over one, two or more guide drums *n*. An arm *o* formed on the double pawl *i* is adapted to be tripped once in every twenty four hours by means of any suitable mechanism governed by the clock *p*, thus actuating the apparatus, and the data on the tape or band *a* appears behind a window *q* formed in the clock case. By the arrangement of the toothed drum *k* and the escapement devices *i* and *j* between the feed spindle *b* and the winding up drum *d* the tape or band will always be moved an exact and equal amount at each operation of the apparatus, thus avoiding the difficulty due to the accumulation of errors of travel which would otherwise occur owing to the variation of circumference of the tape or band on the spindle *b* and drum *d* as the feed takes place from one to the other. The spring in the drum *d* will always keep the tape or band taut.

Suitable constructions and applications of the invention can be adapted for use at railway stations for advertising the departure and arrival of trains, in churches and the like to announce the numbers of the hymns, and in theaters, music halls, concert halls, picture palaces and other places of amusement for announcing the names and characters of the players, the names and numbers of the turns, the titles of pictures and so on; for advertising purposes in public places, on board ships, trains and road vehicles, in which latter cases the apparatus can be arranged, for showing a series of advertisements for certain predetermined intervals of time running through a number of the advertisements up to the capacity of the apparatus. A suitable method of effecting alteration of the indicating apparatus at irregular intervals of time would be to employ one

or more drums or disks having one or more holes drilled at regular distances on the circumference representing time intervals. For instance, if twenty four disks or drums were employed they could be divided into sixty equal parts representing minutes, and each disk representing one hour. A large disk or drum containing divisions sufficient for the whole day could be employed if desired, the time intervals being arranged according to requirements. Suitable plugs forming cams could then be inserted in the holes according to the time which could be clearly marked on the drum or disk, so that as the disk revolved it would operate in turn levers which would control the mechanism of the apparatus. Thus, if it were desired to operate at 5.50, a plug would be inserted in the disk corresponding to hour number "5" and minute number "50". In the case of hour disks, it would of course be necessary to revolve these by suitable means once every hour; if three hour disks are used, then once every three hours, and so on.

In the case of a large apparatus, the arm *o* may be tripped by mechanism actuated by an electric motor, water-motor, clock-work motor, or other power producer which is in turn controlled by clockwork or other escapement mechanism in the immediate locality or at a distance.

It is obvious that provision can be made for illuminating the exposed part of the announcements either from the inside or the outside of the apparatus, and if desired, suitable arrangements may be made to automatically cut off the light at definite times, such as when the announcements are changing. More than one apparatus may be actuated from a common power mechanism.

It will be appreciated that the rolls and the tape may be so mounted that each roll rotates on a horizontal, vertical or inclined axis, or the tape travels horizontally, vertically or diagonally, and that the inscriptions on the tape may be arranged in any order thereon, such as longitudinally as above-mentioned, or as shown in Fig. 4, or diagonally, laterally or otherwise as desired.

What I claim is:—

A calendar or calendar clock comprising in combination a casing, clockwork mechanism in said casing, a support secured within the casing, a plurality of spindles each secured by one of its ends of said support, a feed roll rotatably mounted on one of said spindles, a spring actuated barrel mounted on another of the spindles, a drum removably mounted on said spring barrel and rotated by the latter, a rolled strip of material which bears the dates removably located on one of the spindles, guide rollers mounted on certain of the other spindles and over which the strip passes, said strip passing over the feed roll and winding on the

drum under the action of the spring barrel, the feed roll having teeth which engage perforations in the strip to prevent slipping of the latter, an escapement wheel rotatable 5 with the feed roll, a spring-pressed pivoted escapement lever having two lugs which co-operate with the teeth on the escapement wheel, said escapement lever having an extension adapted to be periodically tripped 10 by the clockwork mechanism, to permit the feed roll, the spring barrel and the drum on the latter to feed the strip the distance between two teeth on the escapement wheel, a ratchet wheel rotatable with the

spring barrel, a spring-pressed pivoted 15 pawl engaging said ratchet wheel, and a fly nut for turning the spring barrel in one direction on its respective spindle and winding the spring therein, the co-operation of the teeth on the feed roll 20 with the perforations in the strip, and of the escapement lever with the escapement wheel insuring that the strip is moved an exact and equal amount at each operation of the apparatus. 25

In testimony whereof I have hereunto signed my name.

HARVEY JAMES MILES.
